United States Patent Office

Des. 219,511
Patented Dec. 22, 1970

219,511

CHAIR

Morris F. Fisher, Carmel, Ind., assignor to Mohasco Industries, Inc., Amsterdam, N.Y., a corporation of New York

Filed Nov. 24, 1969, Ser. No. 20,261

Term of patent 14 years

Int. Cl. D6—01

U.S. Cl. D15—11

The figure is a perspective view of a chair illustrating my new design. The back of the chair is conventionally plain while the side not shown is substantially identical to the side shown, the handle on the side shown not being present on the side not shown.

I claim:

The ornamental design for a chair, as shown and described.
